UNITED STATES PATENT OFFICE

138,180

DESIGN FOR A DENTAL PLATE CONTAINER

Samuel Gordon, Stamford, Conn.

Application January 20, 1944, Serial No. 112,282

Term of patent 14 years

(Cl. D24—1)

To all whom it may concern:

Be it known that I, Samuel Gordon, a citizen of the United States, residing at Stamford, in the county of Fairfield and State of Connecticut, have invented a new, original, and ornamental Design for a Dental Plate Container, of which the following is a specification, reference being had to the accompanying drawing forming part thereof.

Figure 1 is a perspective view in open position of a dental plate container showing my new design.

Figure 2 is a top plan view thereof with the top removed, and

Figure 3 is an end view thereof in closed position.

I claim:

The ornamental design for a dental plate container, as shown.

SAMUEL GORDON.
